UNITED STATES PATENT OFFICE.

HIRAM PERCY MAXIM, OF HARTFORD, CONNECTICUT, ASSIGNOR TO THE COLUMBIA AND ELECTRIC VEHICLE COMPANY, OF SAME PLACE AND JERSEY CITY, NEW JERSEY.

DESIGN FOR A DIAL FOR ELECTRIC METERS.

SPECIFICATION forming part of Design No. 31,919, dated December 5, 1899.

Application filed October 27, 1899. Serial No. 734,988. Term of patent 14 years.

To all whom it may concern:

Be it known that I, HIRAM PERCY MAXIM, a citizen of the United States, residing in the city of Hartford, county of Hartford, State of Connecticut, have invented and produced a certain new and original Design for a Dial for Electric Meters, of which the following is a specification, reference being had to the accompanying drawings, forming a part thereof.

- o This invention relates to the dials of combination volt and ammeters which are intended to indicate to the observer at a glance both the voltage and the amperage; and it consists in the novel configuration thereof, as shown in the accompanying drawings, in which—

Figure 1 is plan view of a dial which embodies the invention, and Fig. 2 is a cross-section of the same.

- o The dial, as represented in the drawings, is bounded on two sides by arcs of circles *a b*

and the other two sides by lines *c*, which connect the diverging ends of the arcs. Lines *d*, which radiate from the centers of the arcs *a b*, extend inwardly from near the concave edges, 25 and in each series of radiating lines, as at *e* and *f*, respectively, is a conspicuous mark, readily distinguishable from the radiating marks or lines.

The essential features of the design are the 30 opposite convex side lines and the conspicuous mark near each.

I claim as my invention—

The design for a dial for electric meters, substantially as shown and described. 35

This specification signed and witnessed this 24th day of October, A. D. 1899.

HIRAM PERCY MAXIM.

In presence of—

MAUD L. CLARK,
HERMANN F. CUNTZ.
